UNITED STATES PATENT OFFICE.

PERRY C. CHASE, OF UPLAND, CALIFORNIA.

ELECTRIC HEATING DEVICE.

No. 918,732.

Specification of Letters Patent.

Patented April 20, 1909.

Application filed July 23, 1908. Serial No. 445,000.

To all whom it may concern:

Be it known that I, PERRY C. CHASE, a citizen of the United States, residing at Upland, in the county of San Bernardino 5 and State of California, have invented certain new and useful Improvements in Electric Heating Devices, of which the following is a specification, reference being had to the accompanying drawings.

0 My invention relates to improvements in electric heaters and more particularly one which may be immersed in a vessel containing water or other liquid for the purpose of heating the same and which may be readily 15 connected to any electric light socket.

The object of the invention is to provide a portable electric water heater of this character which will be simple and inexpensive in construction and at the same time durable in 20 use and efficient in operation.

With the above and other objects in view, the invention consists of the novel features of construction and the combination and arrangement of parts hereinafter fully described and claimed, and illustrated in the 25 accompanying drawings, in which—

Figure 1 is a perspective view of my improved electric heater; Figs. 2 and 3 are enlarged longitudinal sectional views taken in 30 planes at right angles to each other; and Fig. 4 is a transverse sectional view.

In the drawings 1 denotes my improved portable electric water or liquid heater which is connected by a conducting cord C to a 35 plug P which may be screwed into an ordinary electric light socket. The heater comprises a body through which the water or liquid may freely circulate and which contains suitably connected and arranged 40 resistance coils. The body 1 is preferably of rectangular shape and constructed of an open metal frame 2 of angle metal strips. The open sides or faces of the frame 2 are covered by sheets or plates 3 of mica or any 45 other non-conducting material, which sheets or plates are formed with large holes or openings 4 to permit the water to freely circulate through the body or casing. Arranged within the body are a plurality of coil supporting plates 5 between which are arranged 50 spacing plates 6, the latter being provided to prevent the wires of the coils of adjacent plates 5 from coming in contact with each other and short circuiting portions of said 55 coils, thereby insuring the passage of the current through every portion of each coil.

These plates 5, 6 are preferably constructed of mica and the supporting or carrying plates 5 are of slightly less size than the spacing plates 6 and each has centrally disposed 60 apertures 7 arranged adjacent to its ends, and notches or seats 8 formed in its opposite side edges. A wire 9 is wrapped or coiled around each of the plates 5, its coils being engaged with the seats 8 and thereby properly spaced apart, and its ends being passed through the apertures 7, as illustrated. In each of the spacing plates 6 adjacent to one of its ends is an aperture 10 through which the end of one of the wires 9 may be passed 65 so that such wire can be connected to the corresponding wire on the next adjacent plate 5, as shown at 11. The upper ends of the wires 9 upon the outermost plates 5 are passed through apertures 12 in the upper 70 end plate of the body 1 and suitably connected to the conductors of the cord C, the joint or connection being wrapped or covered by insulating material, as indicated at 13. The lower ends of the wires upon the end- 75 most plates 5 and the wires upon the intermediate plates 5 are connected so that all of 80 said wires will be in the electric circuit.

In using the invention the body 1 is immersed in the water or other liquid to be 85 heated and the current is then turned on by means of the key in the socket in which the plug P is inserted. The resistance offered the current in passing through the wires or coils 9 generates heat in the latter which 90 will quickly heat the water that circulates through the body.

Having thus described my invention what I claim is:

1. An electric water heater adapted to be 95 submerged in a liquid and comprising a perforated body, a plurality of coil carrying plates of non-conducting material arranged in the body in parallel relation and each having its side edges formed with notches, 100 each of said plates also having perforations arranged adjacent its ends, wires having their ends passed through the apertures in said carrying plates and their intermediate portions wound or coiled around said plates 105 and engaged with said notches, and spacing plates composed of non-conducting material arranged within the body between the carrying plates and apertured to receive certain of said wires, the wires of adjacent coils 110 being united and the wires of the outer or endmost coils projecting outside of the body.

2. An electric water heater adapted to be submerged in a liquid and comprising a body of non-conducting material having openings to permit of the circulation of a liquid there-through, a plurality of coil carrying plates of non-conducting material arranged within the body in parallel relation, wires wrapped around said plates to provide heating coils, and spacing plates of non-conducting material arranged in the body between said carrying plates, the wires of adjacent coils being connected and the wires of the endmost coils projecting outside of the body.

3. An electric heater of the character described comprising a body having an open metal frame constructed of angle straps, apertured plates of non-conducting material covering the sides of said open frame, coil carrying plates of non-conducting material arranged within the body, wires wrapped or coiled around said carrying plates, the wires or coils upon the adjacent plates being connected, spacing plates between said carrying plates, and an electric circuit terminal connected with the outermost coils or wires.

4. The herein-described electric water heater comprising a rectangular body consisting of an open metal frame constructed of angle straps and apertured plates of non-conducting material covering the sides of the frame and having their edges seated in the angles

of said straps, the top plate being formed with spaced openings, rectangular coil carrying plates of non-conducting material arranged within the body, said coil carrying plates being of less size than the body and having their side edges formed with notches, said coil carrying plates also having centrally arranged openings adjacent to their top and bottom edges, rectangular spacing plates of non-conducting material arranged in the body between the coil carrying plates, the alternate spacing plates being formed adjacent to their top and bottom edges with openings, wires wrapped around the coil carrying plates and engaged with the notches in the same, the ends of the wires being passed through said openings in the coil carrying plates and in the spacing plates, and the ends of the wires of adjacent coils being united, the ends of the wires of the endmost coils being passed through said spaced openings in the top plate of the body, a plug and a conducting cord between the latter and the ends of the wires of the endmost coil.

In testimony whereof I hereunto affix my signature in the presence of two witnesses.

PERRY C. CHASE.
